ABSTRACT: The disclosed process involves the method of grinding or pulverizing any material which may collect on the bell of a blast furnace and thereby might prevent close contact of the bell with the bell seat. This method comprises imparting to the bell a rotational force just prior to the contact of the bell with the bell seat and thereby this motion of the bell as it comes into contact with the bell seat effects a pulverizing of such material and permits the bell to come into a pressure tight contact with the bell seat.

PROCESS FOR MAINTAINING PRESSURE TIGHT SEAL ON BLAST FURNACE BELLS

This is a divisional application of parent application Ser. No. 511,835, filed Dec. 6, 1965, now U.S. Pat. No. 3,372,918 issued Mar. 12, 1968.

This invention relates to apparatus and the process for operation thereof for maintaining a tight seal on bells used in the operation of blast furnaces. More specifically, it relates to apparatus and process for grinding or pulverizing any material which collects on the bell and otherwise prevents close contact of the bell with the bell seat of the hopper with which the bell is intended to make pressuretight contact.

With the advent of high pressure operation of blast furnaces which increases the production capacity and effects other improvements in the operation of the furnace, it is imperative that the bell used in preventing escape of the pressurized gas within the blast furnace while the charge is being added is capable of effecting a seal between the bell and the seat against which the bell is intended to rest. This is necessary in order that the desired high pressure can be maintained over a long period of time, that is for the period between relining of the furnace, which is 2 to 5 years depending on the type of furnace operation.

Very often the escape of gas and dust is caused by the accumulation of foreign material on the surface of the bell. Such material keeps the bell from making the desired close contact and sealing relationship with the bell seat. As a result, "wire drawing," (a term used to describe the escape of gas and dust through a hole or crack in the furnace) commences with accompanying erosion of the bell in the adjacent areas. This erosion eventually causes leakage even when the surface of the bell is clean. This results in increasing amounts of "wire drawing" and accelerates the wear or erosion on the bell or bell seat.

It is presently common practice in such cases to gradually lower the top pressure of the furnace to insure that the bell and seat last until it is time to shut down the furnace for rolling. Because of the lowering of the pressure in the furnace, either intentionally to decrease the wire drawing, or as a result of the considerable escape of gas from the top of the furnace, the production of the furnace is gradually decreased. Obviously, therefore, this escape of gas or "wire drawing" and the accompanying erosion interfere with the production capacity of the blast furnace.

In accordance with the present invention, it has been found that the surface of the bell coming into contact with the bell seat can be kept clean of foreign material, which would otherwise prevent a gastight seal, by imparting to the bell just prior to its coming into contact with the seat a small degree of rotation, namely 1-10 degrees, just sufficient to grind together the respective surfaces and thereby clean, grind or lap the sealing surfaces of the bell and the bell seat of the hopper each time the bell is closed.

While bells have previously been rotated for other purposes and in other manners, the timing of the rotation in order to create a grinding effect between the surfaces of the bell and the bell seat and to effect only a small degree of rotation sufficient to produce the grinding effect, has not previously been contemplated. For example, the small bell has been rotated 90° or 180° in order to distribute the charge and thereby prevent uneven distribution in the furnace bed. There the degree of rotation is much greater, and much sooner in the sequence of operation of the bell than in the present invention. Moreover, in the present instance, the manner of imparting the rotation to the bell is particularly timed and designed to effect the rotation just prior to the contact of the bell with the bell seat thereby effecting the grinding and also using the friction of the surfaces to stop the rotation of the bell.

Since the large bell in a blast furnace of present day design weighs approximately 25 tons, and is supported by a rod of relatively small diameter and approximately 40 foot long, the effect of rotating the bell is similar to having a fly wheel in movement. As a result, there is considerable energy for effect-

ing the grinding action between the contacting surfaces and thereby pulverizing any foreign material on either of the surfaces. The lapping effect also aids in smoothing into any pitted or eroded areas whatever foreign material might be on the surfaces. This aids in effecting a seal between the surfaces.

The desired degree of rotation and timing of the rotation is effected by an adjustable slanted cam which presses against a lever arm as the rod supporting the bell moves upward in effecting the closing of the bell. This lever arm is in contact with and appropriately actuates a clutch which effects the turning of the supporting rod for the bell. This clutch is turned by the lever arm. The clutch rotates the supporting rod only during the upper passage of the rod. During the downward passage of the supporting rod the clutch rides freely.

As indicated above, the turning of the blast furnace bells for the prior art purpose of distributing the charge as suggested by various references, involves the turning of the bell at least 90° between opening and closing the bell, in order to effect more even or uniform distribution of the charge into the blast furnace.

In most cases in these prior art designs, the small bell is adapted to turn and effect discharge of its load onto the big bell thereby distributing the charge evenly on the big bell which, upon lowering, discharges the load into the blast furnace. In all such cases, the turning or the rotation of the bell is effected on the auxiliary bell. In one case, namely U.S. Pat. No. 1,811,702, to Andrews, the charging chute 15 is rotated. In this same design the big bell is also rotated, but in this case the big bell has an oblong configuration instead of the conical design generally used, and is rotated at least 90° in each sequence of opening and closing of the bell. Moreover, the purpose for rotating the large bell is likewise to effect a more even distribution of the charge into the blast furnace. This is accomplished by the fact that some of the material drops off the short dimension, or side 34, and some of the charge drops off the edge of the longer dimension so that this latter material is distributed closer to the sidewalls of the blast furnace. None of these devices show an arrangement or method of rotating the bells only a few degrees and only just prior to the meeting of the surfaces of the bell and the bell seat.

In present day design, the main bell has a diameter of at least about 12 feet and a weight of at least about 15 tons. The bell is supported by a rod of relatively small diameter. The rotation of the rod about its linear axis produces a torque in the rod. Because of the large weight and large diameter of the bell the inertia of the bell at rest is not overcome immediately upon turning of the rod at its upper end. Since the bell does not turn immediately, a twisting torsion is created in the rod. Consequently, it is in the last part of the upward movement of the bell that the rotation of the bell is effected. This rotation occurs just prior to and at the time of contact of the bell with the bell seat.

As stated above the rotation of the bell is effected through only a few degrees. This degree of rotation is, at the time of contact, only enough to effect a small amount of grinding between the surfaces before the frictional forces bring the bell to a stop. If rotation is much greater after contact the abrasion of the bell and bell seat is excessive. The rotation has been found generally satisfactory at 1°-2° but in no case over 10°.

In the drawings:

FIG. 1 is a front elevational view of the top part of a blast furnace showing the respective charging devices.

FIG. 2 is a perspective view of the rotating means portion of FIG. 1.

FIG. 3 is a top cross-sectional view of the rotating means portion of FIG. 1 taken at lines 3-3.

FIG. 4 is an enlarged view of the rotating means portion shown in FIG. 1 showing the adjustable cam and clutch which effect rotation of the supporting rod and large bell.

FIG. 5 shows a side elevational view of the adjustable cam and supporting structure taken at line 5-5 of FIG. 4.

The invention is best illustrated by reference to these drawings.

In FIG. 1, hopper 1 is shown as the charge inlet for blast furnace 2 with large bell 3 shown in position to seal the hopper from the interior of the blast furnace. This large bell 3 is supported by rod 4 which in turn is supported by rod 4' connected to rod 4 through rotating device 5. Lever 6 is connected to the top of supporting arm 4' and is used to raise and lower the bell 3 through supporting rods 4 and 4'.

Chute 7 feeds into the top of hopper 1 upon lowering of auxiliary bell 8 supported by sleeve 9 which encircles rod 4. Sleeve 9 and the auxiliary bell are raised and lowered by a means which, for purpose of simplicity, is not shown in the drawing. Funnel 10 feeds into the top of chute 7. The charge is emptied into the chute by a standard type of skip which is not shown in the drawing.

In the rotating device shown in greater detail in FIGS. 2, 3, 4 and 5, lever 11 is fastened to the top of supporting rod 4 by means of overrunning clutch 12. Clutch 12 will turn in one direction by movement of lever 11 to effect rotation of the supporting arm 4 and also bell 3 supported thereby, but when lever 11 is rotated in the opposite direction, the clutch rides freely without turning supporting rod 4. Lever 11 and clutch 12 ride up and down as the bell is raised or lowered. Yoke guide 13 is fixed to an independent support 14 which does not move with any movement of supporting rod 4 or bell 3. Adjustable cam 15 is fastened to support 14 by the welding of angle clip 16 to support 14.

While supporting rods 4 and 4' and turning device 5 move up and down with the movement of the large bell, yoke guide 13 and adjustable cam 15 are fixed in position. Crossbar 17 has a groove 18 therein by which this crossbar fits around a portion of yoke guide 13 and moves along the length thereof. Lever 11 also has a groove 19 at the end thereof in which adjustable cam 15 is received.

As lever arm 11 passes up and down in accordance with the movement of the large bell 3 and its supporting devices, one of the side walls 20 of groove 19 comes into contact with adjustable cam 15. Cam 15 is adjusted to such a position that when lever 11 travels upward, toward the end of its upward path, cam 15 comes into contact with sidewall 20 of lever 11. A force is imparted thereby through lever 11 and clutch 12 to rotate supporting rod 4, and eventually the large bell 3 is rotated a few degrees just before the bell 3 comes into contact with bell seat 3' at the bottom of hopper 1.

At the bottom of supporting arm 17', there is supported a "Selsyn" transmitter which transmits a signal of rotary motion to a "Selsyn" receiver (not shown) located on the furnace operating floor. This device indicates how fast the bell is rotating, and how much it rotates for each closing operation of the bell.

To overcome frictional forces, there is incorporated into the supporting structure a large antifriction self-aligning bearing 27 which supports the bell and bell rod. The overrunning clutch 12 rotates the large furnace bell, preferably clockwise, as the bell is being closed on the upstroke. As pointed out above, the clutch is activated by the lever 11 which is keyed to the driving case of the clutch. The inner hub of the clutch is

keyed to the bell rod. The lever 11 actuates the clutch to turn rod 4 only on the upstroke and this in turn as explained above turns the large bell only toward the end of the upstroke. On the downstroke, the lever arm rotates in the reverse direction but does not actuate turning of the rod 4 or the bell 3 since the clutch moves freely in this direction.

The amount of rotation and the rotary acceleration can be adjusted by changing the slant of the adjustable cam or wedge bar or even its shape.

10 The rotary motion of the bell is stopped by the sliding of the bell on the bell seat of the bell hopper. This sliding motion cleans, grinds or laps the sealing surfaces of the bell and of the bell seat each time the bell is closed. Coke, lime dust and moisture on the bell serve as lapping compound. This intermittent but unidirectional continual grinding action as the bell is rotated upon coming into closing contact with the bell seat assures a tight seat-seal and minimizes, and often completely overcomes, the possibility of wire-drawing caused by escaping dust laden gases from high pressure blast furnaces, thereby minimizing or avoiding the resulting erosion described above.

15 In a typical blast furnace operation operating according to this invention, it is found that the large bell makes about four complete revolutions per week, which involves about 1400 closing operations of the bell. It is found that the bell turns about 1° each time it is closed, which means a travelling distance of 1.5 inches on a 16 ft. diameter bell seat. With such operation, the wire-drawing is practically eliminated.

20 In operating the main bell in accordance with this invention, it is found that only a few degrees of rotation are required to produce the grinding effect which pulverizes the foreign material on the surfaces of the bell and the respective bell seat so as to effect a much more efficient gas seal. Advantageously, the arc of rotation is in the range of 1° to 10°. A suitable practice is found to be a rotation of approximately 1°.

25 While certain features of this invention have been described in detail with respect to various embodiments thereof, it will, of course, be apparent that other modifications can be made within the spirit and scope of this invention and it is not intended to limit the invention to the exact details shown above except insofar as they are defined in the following claims.

30 I claim:

1. A process for improving the pressure seal between the main bell and the corresponding bell seat of the charging apparatus for a pressurized blast furnace comprising the step of 35 rotating the main bell of said charging apparatus just prior to and at the moment of contact of the main bell with the corresponding bell seat and allowing the frictional forces between the contacting surfaces of said main bell and said bell seat to act as a brake in stopping said rotation whereby a grinding effect is produced between said surfaces, the rotation of said main bell being in the range of 1—10°.

40 2. A process of claim 1 in which said main bell is rotated through an arc of 1°—2°.

45 3. A process of claim 1 in which said main bell is rotated through an arc of approximately 1°.
